Primary Examiner — Sandra Snapp(74) *Attorney, Agent, or Firm* — Law Office of Alexis J Saenz(57) **CLAIM**

The ornamental design for a selfie massager, as shown and described.

DESCRIPTION

FIG. 1 is a front perspective view of a selfie massager showing the new design in accordance with an aspect of the subject technology;

FIG. 2 is a rear perspective view of the selfie massager of FIG. 1;

FIG. 3 is a left hand side view of the selfie massager of FIG. 1;

FIG. 4 is a right hand side view of the selfie massager of FIG. 1;

FIG. 5 is a top view of the selfie massager of FIG. 1;

FIG. 6 is a bottom view of the selfie massager of FIG. 1;

FIG. 7 is an end view of the selfie massager of FIG. 3 from the right end; and,

FIG. 8 is an end view of the selfie massager of FIG. 3 from the left end.

The broken lines shown represent unclaimed subject matter and form no part of the claimed design.
